UNITED STATES PATENT OFFICE.

JULIAN KENNEDY, OF PITTSBURG, PENNSYLVANIA.

ROLLING-MILL.

No. 836,192.

Specification of Letters Patent.

Patented Nov. 30, 1906.

Application filed August 27, 1903. Serial No. 170,968.

To all whom it may concern:

Be it known that I, JULIAN KENNEDY, of Pittsburg, Allegheny county, Pennsylvania, have invented a new and useful Rolling-Mill, of which the following is a full, clear, and exact description, reference being had to the accompanying drawings, forming part of this specification, in which—

Figure 1 is a side elevation, partly in section, of a universal mill constructed in accordance with my invention. Fig. 2 is a front elevation of the mill viewed from the right of Fig. 1, the gear-casing at the lower part of the figure being in vertical section. Figs. 3, 4, and 5 show a modification in which the pinions are at the upper end of the mill. Fig. 3 is a front elevation, the gear-casing being shown in vertical section. Fig. 4 is an end elevation viewed from the right-hand side of Fig. 3, parts of the apparatus being shown in vertical section. Fig. 5 is an irregular horizontal section on the line V V of Fig. 3, and Fig. 3^a is a diagrammatic view.

Universal mills as heretofore constructed have been objectionable in respect of the complication of their gearing, which have been constructed so as to travel with the vertical rolls in their lateral adjustment, and it is for the purpose of overcoming the difficulties incident to such constructions that I have devised my invention, which consists in the combination of laterally-movable vertical rolls mounted within the housings of the horizontal rolls and pinions mounted in stationary bearings above or below the rolls and connected therewith by movable power connection, so that the rolls can be adjusted to and from each other without moving the pinions. This greatly simplifies the apparatus and provides a mill which is easy to keep in repair and easy to lubricate. It enables me to remove the pinions from direct connection to the rolls and to inclose them, thus obviating the trouble which has been experienced in keeping in order the exposed laterally-moving pinions heretofore employed.

I have shown in the drawings two forms of my invention which I regard as preferable; but those skilled in the art will be able to modify it further to suit the particular uses to which it is to be put.

In Figs. 1 and 2, 2 represents the housing of a universal mill. 3 are the horizontal rolls, and 4 designates the usual feed-rollers.

55 The vertical rolls 5, to which my inven-

tion particularly relates, are journaled in bearings 6 at their lower and upper ends. These bearings are mounted in vertical laterally-movable frames or housings 8, which are set within the housings of the horizontal rolls upon horizontal slide-bars 9 and 10, around which and within the frames 8 I may set bushings 11, by which the friction of sliding is reduced. As the vertical rolls are set within the housings of the horizontal rolls, 65 the mill is rendered very compact and its efficiency and strength is greatly increased. Each of the frames 8 is preferably made in two divided sections held together by bolts 14, so that they may be fitted around the 70 necks of the vertical rolls. At the lower end of each of the vertical rolls is a wabbler connection 15, coupled flexibly with a spindle 16, the connection shown in Figs. 1 and 2 being the same as that for which Letters Patent No. 75 666,144 were granted to me on January 15, 1901; but other suitable wabbler connections may be employed, the purpose being to provide universal joints between the spindles and lower end of the rolls. The spindles are 80 connected at their lower ends by a similar universal joint 17 to the vertical shafts 18 of the pinions 19 and 20. These two pinions are incased in stationary pinion-housings 21, in which they are mounted in vertical bearings, and are geared together. The pinion 20 is connected to or made integral with a beveled gear 22, driven by a beveled pinion 23 on a horizontal shaft 24. The pinions are covered and shielded by a cap 25, and the 85 housing may be charged with oil, so as to immerse the pinions and to keep them perfectly lubricated.

At the base of each pinion-shaft 18 is a step 26, which is vertically adjustable against 95 the shaft by a wedge-nut 27, operated by a screw 28, which extends to the exterior of the pinion-housing and has a squared end 28', by which it may be turned so as to move the wedge-nut 27 in contact with an inclined 100 block 29 at its base, and thus to adjust it vertically.

The pit 30, in which the pinion-housing is set, may be covered with a hood 31 to exclude scale, and the wabbler-joints 16 and 17 may 105 be surrounded by a jointed and flexible casting formed of interfitted parts 32 33. The top openings of the hood around the wabbler-shaft are formed by turret-like projections 34 of sufficient size to allow the neces- 110

sary motion of the spindles and may likewise be protected by a hood 35, set above it on the spindle.

The facility which my invention affords for incasing and protecting the gearing is of great practical importance.

In the use of my apparatus the vertical rolls are driven by power transmitted from the shaft 24 to the gearing 23, 22, 20, and 19, 10 to the spindles 16, and thence to the rolls, which will be driven thereby in every position of their lateral adjustment, which is effected by adjusting mechanism applied to the frames 8 and operated by hand or by suitable motors. For this purpose I may use the adjusting-screws and gearing 36, (shown in Fig. 2,) or I may substitute therefor suitable hydraulic cylinders, the purpose being to move the frames 8 laterally on the slides 9 10,

20 and thus to move the rolls toward and from each other. This motion is permitted by the spindles and their flexible connections 15 and 17. Each vertical roll is preferably supported at its upper end by a collar 42, resting 25 upon an annular bearing 43, having a spherical contour and resting in a spherical cavity on the frame 8, so that by self-adjustment of this universal bearing an even pressure is obtained on the rubbing-surfaces which support 30 the rolls. A ring of vulcanized fiber or other suitable antifriction material 44 is preferably interposed between these rubbing-surfaces.

For the purpose of lubricating the rolls and the pinions I preferably employ the device 35 illustrated in Fig. 1. Each vertical roll has an oil-passage 37 extending through it from top to bottom and having lateral passages 38, leading to the upper and lower roll bearings. Below each of the passages 38 the central 40 passage 37 is plugged, as at 38', so as to cause the oil to pass out through the passage 38 to the necks of the rolls. Below the upper neck of the rolls is a return-passage 38", which leads the oil from the bearing transversely 45 through the body of the roll and back to the passage 37, whence it passes to the bearing of the lower neck and thence into the casing 32, surrounding the coupling 15, whence 50 after filling the cavity of the coupling to the level of a central passage 40 it flows therethrough into the spindle. The oil-passage in

the spindle leads to the coupling 17, where after forming a pool of predetermined depth the oil passes through a passage 38^b to the upper end of the bearing of the pinion-shaft 55 18 and passes thence down into the pool of oil contained in the pinion-housing. Thus by supplying oil to the upper part of the vertical rolls I cause it to pass in series to the several roll-bearings, the spindle connections, 60 and the pinion-bearings without need of separately supplying lubricant thereto.

In the modifications shown in Figs. 3, 4, and 5 the arrangement of the mill is reversed, the stationary bearings for the pinions being 65 at the top of the roll-housing instead of the bottom, as shown in Figs. 1 and 2. In these figures I show two pairs of vertical rolls 5' 5' and 5" 5" on opposite sides of the horizontal rolls, their driving-pinions being 70 shown in diagram in Fig. 3^a. A central driving-pinion B is in gear with the pinions C D of two of the vertical rolls on opposite sides of the horizontal rolls, and these in turn drive the pinions E F of the other two vertical rolls. 75 All these pinions are inclosed in the casing G at the upper end of the roll-housings and are connected with the vertical rolls by spindles 16' and flexible connections or wabblers 15'.

I claim—

1. In a rolling-mill, a vertical roll having a vertical oil-passage therein, a driving-pinion for said roll, a driving-spindle universally jointed to the roll at one end and to the pinion at the opposite end, and also having an oil-passage therethrough, and casings surrounding the universal joints or couplings and having communication with the oil-passages in the roll and spindle; substantially as described. 80

2. In combination with vertical rolls and driving-pinions below the same, a hood having turret-like projections of sufficient size to allow the lateral motion of the spindles, and a second hood on the spindle overlapping 95 said projections; substantially as described.

In testimony whereof I have hereunto set my hand.

JULIAN KENNEDY.
